UNITED STATES PATENT OFFICE.

JAMES J. McLINDEN, OF WATERBURY, CONNECTICUT.

CAN.

No. 820,592.

Specification of Letters Patent.

Patented May 15, 1906.

Application filed September 14, 1905. Serial No. 278,503.

To all whom it may concern:

Be it known that I, JAMES J. McLINDEN, a citizen of the United States, residing at Waterbury, in the State of Connecticut, have 5 invented certain new and useful Improvements in Cans; and I do declare the following to be a full, clear, and exact description of the invention, such as will enable others skilled in the art to which it appertains to 10 make and use the same.

This invention relates to improvements in cans.

The object of the invention is to provide a can which when open for the removal of the 15 contents thereof will be so mutilated as to prevent the refilling of the same without detection, means being provided to facilitate the discharge of the contents of the can after the same has been opened and means for temporarily closing the discharge-opening formed 20 therein.

A further object is to provide a can of this character which will be simple and inexpensive in construction, particularly designed 25 for the reception of ointments, salves, and the like.

With the above and other objects in view the invention consists of certain novel features of construction, combination, and arrangement of parts, as will be hereinafter 30 described and claimed.

In the accompanying drawings, Figure 1 is 35 a side view of a can constructed in accordance with the invention. Fig. 2 is a vertical longitudinal sectional view. Fig. 3 is a top plan view of the can with the temporary cover or closing-cap removed, and Fig. 4 is a detail view of the plunger-rod used in connection with the can.

Referring more particularly to the drawings, 1 denotes the body of the can, in the bottom of which is formed a centrally-disposed aperture 2. Adapted to be placed upon the upper end of the can-body and fixedly secured thereto is a closing-cap or cover 3. The top of the fixed cover or closing-cap 3 is formed of a soft metal and is provided with a series of concentrically-arranged circles 4, which are scored in the upper side of 45 50 said top to facilitate the cutting of different-sized openings therein.

Within the body of the can is arranged a movable bottom or plunger-disk 5, in the under side of which is formed a centrally-disposed recess 6, said recess being adapted to coincide with the aperture 2 formed in the bottom of the can. On the upper end of the can over the fixed cover or closing-cap 3 is adapted to be placed a temporary closing-cap 7, by which the upper end of the can is temporarily closed after being cut open for the removal of a part of the contents of the can, thus preserving the remaining contents therein.

In order to facilitate the discharge of the 65 contents of the can through the opening cut in the top of the fixed closing-cap 3, a plunger-rod 8 is provided. This rod is provided on one end with a head 9, the opposite end of said rod being adapted to be inserted 70 through the aperture 2 in the bottom of the can and in engagement with the recess 6 in said movable bottom or plunger-disk 5, whereby said disk is pushed upwardly in the can-body, thus forcing the contents of the can 75 out through the hole cut in the top of the fixed closing-cap.

When the original contents of a can constructed as herein shown and described has thus been removed therefrom, it will be impossible to refill said can and sell the same 80 without detection.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 90 this invention.

Having thus described my invention, what I claim as new, and desire to secure by Letters Patent, is

The herein-described can consisting of a can-body having a centrally-apertured bottom, a plunger-disk 5 mounted to slide within the can-body and provided with a removable plunger-rod 8 extending through the 100 aperture in the bottom of the can and provided with a head 9, a fixed cap arranged on

the upper end of the can-body and provided with a concentrically-arranged cutting-ring scored into the top of said cap to facilitate the cutting of different-sized discharge-holes therein, and a removable cap adapted to fit over the fixed cap, essentially as described.

In testimony whereof I have hereunto set my hand in presence of two subscribing witnesses.

JAMES J. McLINDEN.
